HUMIDIFIER UNIT RECEPTACLE FOR ATTACHMENT TO HEATING SYSTEM AIR CONVEYING DUCT AND THE LIKE

William B. Morrow, Winston-Salem, N.C., assignor to
Aqua-Mist Incorporated, Winston-Salem, N.C.

Filed May 1, 1972, Ser. No. 249,489

Term of patent 14 years

Int. Cl. D23—04

U.S. Cl. D23—146

FIG. 1 is a perspective view of a humidifier unit receptacle for attachment to heating system air conveying duct and the like showing my new design viewed from above and to one side of the receptacle;

FIG. 2 is a perspective view thereof, viewed from below and at the opposite side of the receptacle; and

FIG. 3 is a side elevation view thereof.

I claim:

The ornamental design for a humidifier unit receptacle for attachment to heating system air conveying duct and the like, as shown and described.
